BOX FOR A CAKE OF SOAP

Corina Ruiz de Lahoud, Madrid, Spain

Application February 1, 1957, Serial No. 44,713

Term of patent 14 years

(Cl. D58—12)

FIG. 1

Fig. 1 is a perspective view of a box for a cake of soap, showing my new design;

Fig. 2 is a perspective view thereof, showing the cover removed from the bottom portion of the box; and

Fig. 3 is an enlarged detailed fragmentary view of the surface ornamentation applied to the cover portion of the box.

The dotted line showing of the cake of soap in Fig. 2 is for illustrative purposes only.

The drawing is shaded to indicate contrasting colored areas.

I claim:

The ornamental design for a box for a cake of soap, substantially as shown and described.
